UNITED STATES PATENT OFFICE.

ARTHUR LANGERFELD, OF NEW BRITAIN, CONNECTICUT, ASSIGNOR TO P. & F. CORBIN, OF SAME PLACE.

DESIGN FOR ORNAMENTATION OF HARDWARE.

SPECIFICATION forming part of Design No. 14,969, dated April 22, 1884.

Application filed March 3, 1884. Term of patent 14 years.

To all whom it may concern:

Be it known that I, ARTHUR LANGERFELD, of New Britain, in the county of Hartford and State of Connecticut, have invented and produced a new and original Design for Ornamenting Articles of Hardware; and I do hereby declare the following, when taken in connection with the accompanying drawing and the letters of reference marked thereon, to be a full, clear, and exact description of the same, and which drawing constitutes part of this specification, and represents a face view of one leaf of a hinge, the ground showing the characteristic feature of this design.

This invention relates to a design for the ornamentation of hardware—such as butts, escutcheons, lock-fronts, knobs, bell-pulls, &c.—and in which the ornamentation is uniform, so that all the hardware in a building or apartment may present the same general style or pattern; and in illustrating the design I show a butt-hinge, which will be sufficient to show the manner in which the design may be applied to various articles of hardware; and the design consists in the representation of lattice. (Shown at a.)

Said design may be further described as

consisting of an even ground, upon which is formed a diagonal lattice-work. Raised dots, representing the heads of nails, screws, or rivets, are placed at the several crossings of the bars or slats of the lattice. This representation of lattice-work forms a diaper pattern, which is used for filling panels and spaces between other ornaments, such other ornamentation depending upon the shape and size of the article, and constituting no part of the design herein described, it being understood that the lattice-work, as hereinbefore described, constitutes the characteristic or essential feature of this design.

I claim as my production—

The hereinbefore-described diaper design for the ornamentation of hardware, consisting of the even ground having the representation of lattice-work, with raised dots representing the heads of nails, screws, or rivets on each crossing of slats, as shown in the accompanying illustration, and herein described.

ARTHUR LANGERFELD.
